UNITED STATES PATENT OFFICE.

DOROTHY LONG, OF NEW YORK, N. Y., ASSIGNOR TO FRANKLIN SIMON & COMPANY, INC., OF NEW YORK, N. Y., A CORPORATION OF NEW YORK.

DESIGN FOR A DRESS.

Application filed January 8, 1929. Serial No. 29,532. Term of patent 3½ years.

To all whom it may concern:

Be it known that I, DOROTHY LONG, a citizen of the United States, and a resident of the city of New York, in the county of New York and State of New York, have invented the new, original, and ornamental Design for a Dress, of which the following is a specification, wherein a dominant feature of the design resides in the double vest effect with converging lines meeting below the neck opening and positioned to seemingly depend from the fastening members adjacent the neck opening.

Reference is had to the accompanying

drawing, forming part thereof, wherein Figure 1 is a front view of a dress showing my new design, the same being illustrated on a figure indicated by dotted lines;

Figure 2 is a rear view of the dress shown in Figure 1.

I claim:—

The ornamental design for a dress substantially as shown and described.

Signed at New York, in the county of New York and State of New York this 5th day of January A. D. 1929.

DOROTHY LONG.
